TUBE PASTE DISPENSER

John D. O'Neill, Missoula, Mont.

Application January 25, 1940, Serial No. 315,586

2 Claims. (Cl. 221—60)

This invention relates to a dispensing device designed primarily for use in supporting and dispensing pastes and semi-liquid materials contained in tubes.

The primary object of the invention is to provide a support of this character having means to grip one end of the tube containing paste or semi-liquid material, the means embodying a key to be rotated to compress the tube, forcing the material therefrom.

Another object of the invention is to provide a device of this character wherein the key will be supported in a true horizontal plane at all times, thereby eliminating any possibility of the key twisting, as it is being rotated to eject the material from the tube.

A still further object of the invention is to provide a combined support and dispenser of this character, having a discharge opening, and a sliding closure operating adjacent to the opening, the closure being operated by contact of an article thereagainst, such as a tooth-brush or the like, so that the material dispensed, will be directed to the bristles of the tooth-brush or article on which the material is deposited.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is an elevational view of a combined paste tube support and dispenser, constructed in accordance with the invention.

Figure 2 is a sectional view taken on line 2—2 of Figure 1.

Figure 3 is a bottom plan view of the device.

Figure 4 is a transverse sectional view taken on line 4—4 of Figure 1.

Figure 5 is a sectional view taken on line 5—5 of Figure 2.

Figure 6 is a sectional view through the carriage on which the key is supported.

Referring to the drawings in detail, the device comprises a box-like body portion, the front thereof being open. The body portion includes a rear wall 5, side walls 6, a top 7, and a bottom 8. The bottom 8 is formed with a passageway 9 which is extended at an oblique angle with respect to the front and rear walls of the bottom 8, portions of the passageway being vertical, one end

of the passageway being threaded as at 10. The bottom 8 is formed with inwardly disposed parallel flanges 11 providing a support for the sliding closure 12, the sliding closure being normally urged towards the front edge of the body portion, by means of the coiled spring 13. A stop indicated at 14 is formed adjacent to the front edge of the body portion, and provides an abutment against which the forward edge of the sliding closure 12 engages, restricting forward movement of the sliding closure.

As clearly shown by Figure 2 of the drawings, the sliding closure 12 is formed with a depending extension 15 provided with a forwardly extended lip 16 that provides a rest for an article, such as the tooth-brush indicated at A and shown in Figure 1 of the drawings.

Guide rods indicated at 17 extend inwardly from the rear wall 5 of the body portion, and provide a support for the carriage 18 on which the pressure rollers 19 are mounted. The carriage includes horizontal arms 20 which are secured to the tubular bearings 21 that in turn are mounted on the guide rods 17 to move longitudinally thereof. Extending upwardly from the arms 20, is a frame indicated at 22 formed with a curved bearing surface 23 that provides a support for the key indicated at 24. This key, extends through the body portion and is provided with enlargements 25 that are disposed in the guideways 26 formed within the body portion and disposed adjacent to the side edges thereof. The guideways and enlargements are of such construction that the key will be held in a true horizontal position at all times, eliminating any possibility of the key twisting, as it is being moved through the housing or body portion. As shown, the key is formed with a longitudinal slot 27 into which the crimped end of a paste tube is positioned, so that when the key is rotated, the tube will be wound on the key, feeding the carriage longitudinally of the housing or body portion. The pressure rollers 19 operate in advance of the key, and are designed to exert pressure on the tube supported within the body portion, to squeeze the contents of the tube therefrom.

On one end of the key 24, is a finger piece 28 that is disposed exteriorly of the body portion, so that it may be gripped by the operator to rotate the key and accomplish the purpose of the invention.

In order that the key may slide longitudinally of the body portion, elongated openings 29 are formed in the partitioning members 30 and one side wall of the body portion, so that the key

may move longitudinally of the body portion when it is being rotated to force material therefrom.

In the use of the device, it will of course be understood that a suitable bracket or support will be provided so that the body portion may be secured to a supporting surface. The tube to be used with the device is now positioned by threading the nozzle thereof into the threaded opening 10 of the passageway 9. The crimped end of the tube is now positioned within the slot of the key, and the rollers 19 forced over the tube.

By rotating the key, it is obvious that pressure will be directed to the tube, forcing material therefrom to fill the passageway 9. When an article such as a tooth-brush is positioned against the depending extension 15, and the tooth-brush forced inwardly, the sliding closure will be moved to uncover the discharge end of the passageway 9, allowing a quantity of the material to pass onto the toothbrush.

When pressure on the tooth-brush is released, the sliding closure 12 will be returned to its closing position by the action of the coiled spring 13. The ribbon of paste or material passing from the passageway 9, will be cut off to prevent an excessive quantity of material being dispensed.

What is claimed is:

1. A paste tube support, comprising a body portion, vertical guide rods secured within the body portion and supported on the rear wall thereof, a vertically movable carriage including supporting arms, vertical tubular bearings on the inner ends

of said arms, said bearings having openings through which the guide rods extend, holding the carriage in alignment with the walls of the body portion, a key having a slot in which one end of a paste tube is held, the ends of the key being rotatably supported in the carriage, and pressure rollers mounted on the carriage and between which

5 said tube is pressed when the key is rotated on the carriage, whereby paste is forced from the tube.

2. A paste tube support comprising a body portion, vertical guide rods secured to the rear wall of the body portion and disposed in parallel spaced relation with respect to each other, said rods being also spaced from the rear wall of the body portion, a carriage including end members, supporting rods forming a part of the end members, tubular bearings on the inner ends of the supporting rods and adapted to receive the first 15 mentioned rods, slidably mounting the carriage on the vertical rods, horizontal rods connecting the end members, rollers on the last mentioned rods, said rollers operating in parallel relation with respect to each other, said end members of the carriage having curved upper surfaces, a key 20 resting in the curved upper surfaces of the end members, said key having a slot in which one end of a paste tube is held, and said key adapted to wind the paste tube on the key, forcing material 25 from the tube, and pressure rollers mounted on the last mentioned horizontal bars for directing a pressure to the tube in advance of the key.

JOHN D. O'NEILL.
